Patented Aug. 1, 1922.

INVENTOR

Maximilian N. Faulk

W. B. Williamson

UNITED STATES PATENT OFFICE.

MAXIMILIAN N. FAULK, OF PHILADELPHIA, PENNSYLVANIA.

WHEELED TOY.

1,424,396.

Specification of Letters Patent. Patented Aug. 1, 1922.

Application filed December 17, 1920. Serial No. 431,317.

To all whom it may concern:

Be it known that I, MAXIMILIAN N. FAULK, a citizen of the United States, residing at Philadelphia, in the county of Philadelphia 5 and State of Pennsylvania, have invented new and useful Improvements in a Wheeled Toy, of which the following is a specification.

My invention relates to a new and amusing wheeled toy for use of children in playing with sand and consists of a yoke, portions of which are shaped to represent horses' heads and having a handle rigidly attached thereto, the yoke having a container or bucket suspended within the same and so arranged as to always maintain an upright position regardless of the position assumed by the yoke.

A further object of the invention is to provide in a toy of the character stated, a yoke mounted on wheels, portions of said yoke acting as supports when in an upright position to maintain the toy in such position during the loading or unloading of the receptacle suspended within said yoke other portions of said yoke forming a hand hold so that the toy may be transported from place to place.

A further object of the invention is to provide a toy including a yoke in which is suspended a receptacle or bucket the center of gravity of which is below the pivot points thereof.

With these ends in view, this invention 35 consists in the details of construction and combination of elements hereinafter set forth and then specifically designated by the claim.

In order that those skilled in the art to 40 which this invention appertains, may understand how to make and use the same, I will describe its construction in detail, referring by numerals to the accompanying drawing forming a part of this application, in 45 which:—

The figure is a perspective view of my new and amusing toy.

In carrying out my invention as here embodied, 2 represents a yoke comprising side members 3 each of which is shaped to represent the head of a horse and to the rear ends of which is rigidly secured a cross piece 4 the inner edge 5 acting as a hand hold whereby the toy may be transported from 55 place to place after the manner of a bucket or basket. To this cross piece is rigidly

secured a suitable handle 6 whereby the toy may be pulled or pushed about as will be readily understood by the following description; and this handle carries a suitable rest 60 7 to hold the handle in a certain raised position.

Between the side pieces 3 adjacent their outer or rear ends is fastened a suitable brace 8 for holding said side pieces in their 65 parallel positions and also for properly strengthening the same.

On the outside of the side pieces 3 adjacent their outer or rear ends are located a pair of wheels 9, one of which is on each side 70 of the yoke and are journalled on suitable axles 10 which, as here shown, may be screws and screwed into the side pieces of the yoke so as to properly support the latter and the outer ends of the side pieces act as supports 75 or rests when the yoke is in an upright or vertical position since said outer ends are so positioned as to engage the surface on which the toy rests when said yoke is in the upright position.

Between the side members 3 of the yoke is suspended a suitable receptacle or bracket 11 by means of trunnions 12 which act as pivots for said receptacle and these trunnions may be in the form of rivets or screws. 85 The pivot points of the receptacle are above the center of gravity of said receptacle so that it will always remain in an upright position regardless of the position in which the yoke may be placed.

In practice the toy may be placed in an approximately horizontal position by bringing the rest 7 into engagement with the surface on which the toy rests at which time the receptacle may be filled with sand, pebbles or other objects and transported from place to place and readily dumped by tipping the receptacle. Instead of pushing or pulling the toy upon the wheels the yoke may be raised to a vertical position and the 100 toy then carried by gripping the hand hold after the manner of bucket or basket.

Of course I do not wish to be limited to the exact details of construction as herein shown as these may be varied within the 105 limits of the appended claim without departing from the spirit of my invention.

Having thus fully described my invention, what I claim as new and useful is:—

A toy comprising a yoke consisting of side 110 pieces, a brace secured to said side pieces adjacent their outer ends and a cross piece

at the opposite ends thereof, the inner edge of said cross piece acting as a hand hold, a handle fixed to said cross piece, a rest attached to said handle, wheels, axles for said 5 wheels carried by the side pieces, said wheels being so positioned relative to the outer ends of the side pieces that said side pieces will engage the surface on which the wheels rest

and act as supports when the yoke is in an upright position, a receptacle, means for pivoting said receptacle between the side pieces of the yoke above the center of gravity of said receptacle.

In testimony whereof, I have hereunto affixed my signature.

MAXIMILIAN N. FAULK.
